UNITED STATES PATENT OFFICE.

FREDERICK F. COUCH, OF NEW BRUNSWICK, NEW JERSEY, ASSIGNOR TO FEDERATED ENGINEERS DEVELOPMENT CORPORATION, OF JERSEY CITY, NEW JERSEY, A CORPORATION OF DELAWARE.

VALVE.

Application filed March 13, 1925. Serial No. 15,252.

My invention relates to a valve adapted particularly for controlling motors operated by liquid motive agents, although my invention could also be used on motors driven by gaseous motive agents.

The present invention belongs to that class having a self-operating distributor valve member and a pilot valve, the latter serving to initiate movement of the distributor valve, and the present invention is an improvement on the invention described in my co-pending application, Serial No. 758,641, filed December 29, 1925.

It is an object of my present invention, to provide a valve mechanism in which seating of the distributor valve will be positively assured.

It is also an object of my invention to provide a valve mechanism in which a minimum quantity of motive agent is employed for the operation of the valve.

Another object of the invention, is to reduce the friction of moving parts.

A further object is to provide a construction in which the leakage of motive fluid through or past the valve members will be reduced to a minimum.

A still further object is to provide a construction in which wear of parts will be automatically taken up.

In addition to these, another object of my invention is to provide a construction in which the cost of manufacturing the parts and assembling them, is reduced to a minimum.

With these and still other objects in view, my invention consists in certain novel features of construction and combinations and arrangements of parts as will be more fully hereinafter described and pointed out in the claims.

In the accompanying drawings:

Figure 1 is a sectional view of a hydraulic motor with my improved valve applied thereto. The lower portion of the motor casing being broken away;

Figs. 2 to 4 inclusive are views of my improved valve in vertical section, showing successive positions of the distributor valve member and the pilot valve member;

Fig. 5 shows an enlargement of a portion of Fig. 1;

Fig. 6 shows an enlargement of a portion of Fig. 3; and Fig. 7 is a perspective view

of a plate constituting a part of the pilot member.

Referring to Figure 1, I have shown a form of hydraulic motor similar to that illustrated in the above mentioned co-pending application. The motor is provided with a double walled casing 10 forming a water jacket 11 and a water space 12. The upper end of the casing is open and is adapted to receive a cylinder casting consisting of a plate 13 mounted on the top of the casing and a depending cylinder 14 which projects into the water space 12. In the cylinder 14, a piston 15 is fitted. The piston is mounted on a rod 16 which passes through a stuffing box 17 formed in the bottom wall of the motor casing. At one side of the motor casing there is an inlet port 18 communicating with the water space 12 and with a port 19 leading through plate 13 to my improved valve mechanism. At the opposite side of the casing there is an outlet port 20 leading from the valve mechanism through plate 13 to the water jacket 11. The water jacket is provided with a discharge port not shown in the drawing. It will be understood that water under pressure admitted through the port 18 into the water space 12 always exerts an upward pressure against the underside of piston 15. When water under the same pressure is admitted to the upper part of cylinder 14, there is an overbalancing pressure tending to force the piston downward by reason of the fact that the effective area of the lower side of the piston is reduced by the piston rod 16. Reciprocation of the piston is therefore effected by alternately connecting the upper end of cylinder 14 with the port 19 and port 20. This alternation is effected by the valve mechanism.

My improved valve is formed with a casting which may, for convenience of manufacture, consist of four members, indicated by the numerals 21, 22, 23 and 24. The member 21 may be called the cylinder member, as it is formed with two differential cylinders 25 and 26 in which my distributor valve member operates. At the top of the cylinder member, there is an annular member 22 formed on its upper face adjacent its inner periphery with a bead 27, which serves as an upper seat for the distributor valve. Above the member 22 is a cap 23, which serves to close the top of the valve casing.

The three members 21, 22 and 23 are clamped together by means of bolts 28 and suitable packing material may be introduced between them to make the joints water tight. The cylinder member in turn is bolted to the motor casing 10, the bolts not being shown in the drawing.

It will be noted that the cylinder 26 is formed by the cylindrical face of an inwardly projecting annular flange 26' and is of smaller diameter than the cylinder 25. Immediately below this flange, there is a recess 29 which communicates through a passage 30 with port 19. At the opposite side of the casing, there is a passage 31 which connects the upper end of cylinder 25 with the water jacket 11 by way of port 20. Located immediately below the recess 29 is the annular bearing member 24 which is secured to the cylinder member 21. On the lower face of member 24 adjacent its inner periphery, there is a bead 32 which serves as a lower seat for my distributor valve. In the wall of cylinder 25, there is a packing member 33, which may be in the form of a cupped leather ring and a similar packing member 34 is placed in the wall of cylinder 26.

All the parts so far described in connection with my valve mechanism, are stationary members. It will be understood that the lower part of the valve casing 21 is open to the upper end of cylinder 14.

The distributor valve which operates within the differential cylinders 25 and 26 may for convenience of manufacture, be formed of several members, as follows:

There is a hollow cylindrical member 35, having a piston surface 35' fitting the wall of the cylinder 26 and also formed with an annular flange 36, which serves as a piston for cylinder 25. At each end of the member 35 there is a collar 37, the upper collar engaging the inner cylindrical face of the member 22 and the lower collar engaging the inner cylindrical face of member 24. The collars 37, however, are peripherally grooved as indicated at 37' so as to permit water to pass by them. The grooves 37' however, do not extend to the very outer extremities of the collars but terminate in an annular groove 38, formed just below the top of upper member 37 and just above the bottom of the lower member 37, leaving an ungrooved piston valve surface 38' at the outer end of each member 37. The groove 38 provides a common communicating channel for all the grooves 37'. Annular cap members 39 are fitted upon the opposite ends of the distributor valve and between each cap 39 and the adjacent member 37 is a spring metal washer 40, the washer being clamped at its inner periphery between shoulders formed on the members 39 and 37. The outer edge of the washer 40 is thus free to

be flexed up or down out of its normal plane. The various members of the distributor valve are held together by bolts 41, which pass from the top member 39 to the bottom member 39, holding all parts securely together. The washers 40 are adapted alternately to engage the beads 27 and 32 on annular members 22 and 24.

Mounted to operate within the bore of the cylindrical member 35 is my pilot valve 75 which consists of two narrow plates 42 carried by a cage 43. Projecting from the upper face of piston 15, is a valve stem 44 which passes through the lower wall of the cage 43. This stem is provided with stop members 45 and 46, which are so spaced as to provide considerable lost motion between the stroke of the piston 15 and that of the pilot valve. The slide valves 42 are arranged to reciprocate in contact with seats 85 35' (see Fig. 5) formed on the inner face of the member 35, and each slide valve is pressed against its seat by a spring 47 carried by the cage 43 and bearing against the rear face of the slide valve 42.

In each valve seat there are three ports 48, 49 and 50, which are controlled by the slide valve 42. The port 49 is always in communication with the recess 29. The ports 49 and 50 penetrate the wall of the member 35 below and above the piston 36 respectively. In the contact face of each slide member 42, there is a groove 51, which is always in communication with port 49 and is alternately in communication with ports 50 and 48, depending upon the position of the piston 15.

It will be understood that the cage 43 does not completely fill the hollow interior of the member 35 and consequently the upper end of the cylinder 14 is always in communication with the space 52 at the top of the valve casing.

The operation of my improved valve can now be understood by noting successive positions of the various parts thereof in the successive views of the drawings.

Figure 1 represents the position of the valve parts just as the piston 15 has reached the bottom of its stroke. The distributor valve is in its lower position with the upper spring washer 40 bearing upon the bead 27. As shown more clearly in Fig. 5, the pressure upon the top of the distributor valve is such as to flex the washer 40 insuring a positive seating on the bead 27, even though the distributor valve as a whole might be slightly canted, owing either to imperfect manufacture or to slight wear between the inner periphery of members 22 and 24 and the outer peripheries of members 37.

As shown in Fig. 1, the slide valves 42 have been drawn down by the piston 15 until the grooves 51 have just uncovered the

lower ports 48. This immediately establishes communication between passage 30 and the lower end of cylinder 25 by way of ports 49. Water under pressure entering the cylinder 25 below the piston 36, forces the distributor valve upward to the position shown in Fig. 2. As the distributor valve rises, the ports 48 which were just cracked open by the downward movement of the slide valves 42, are opened wide and remain open throughout the upward movement of the distributor valve. In other words, once the ports 48 are cracked open, they open themselves fully regardless of the movement of the slide valve 42. Upward movement of the distributor valve is also assisted by the upper spring washer 40, which, as shown in Fig. 5, has been flexed and is under a tension which endeavors to restore the washer to its normal plane. Thus the spring washer assists in assuring a positive upward movement of the distributor valve as soon as the ports 48 are cracked open.

It will be understood of course, that the distributor valve rises because the difference in pressures acting on the piston 36 overbalances the downward pressure acting on the annular surface of the member 37. The distributor valve rises until the lower washer 40 engages bead 32, as shown in Fig. 2, and the pressure on the bottom of piston 36 is sufficient to flex the lower washer downwardly as shown in the detail view Fig. 6. When the parts are in the position shown in Fig. 2, communication between passage 30 and the top of cylinder 14, by way of grooves 37' in the lower member 37, is interrupted, and instead, the cylinder is connected with the exhaust passage 31 by way of the grooves 37' in the upper member 37.

As explained above, the cage 43 does not completely fill the hollow interior of the member 35 and consequently the cylinder 14 is always in communication with the space enclosed by the cap 23. Therefore, when the parts are in the position shown in Fig. 2, water is freely discharged from the upper end of cylinder 14 through the upper grooves 37' as the pressure on the bottom of the piston 15 causes the piston to rise. The valve parts remain stationary in the position shown in Fig. 2 until the stop 45 engages the bottom of cage 43 near the end of the upward stroke of piston 15. Thereupon the cage 43 is raised to the position shown in Fig. 3. This action serves to cut off the ports 48 and open ports 50 to communication with ports 49 by way of grooves 51. As soon as ports 50 are cracked open, the water in the piston 26 is free to discharge into the upper end of cylinder 25 and thence to exhaust passage 31. Thereupon water pressure against the upper end of the lower member 37 forces the distributor valve downward and by this movement it is assisted by the tension of the lower flexed washer 40. Furthermore, as soon as the distributor valve starts moving, the ports 50, although they may have been barely cracked open by the slide valves 42, will open themselves fully, insuring a free passage of water out of the space under the piston 36. The distributor valve is thus moved down to position shown in Fig. 4, which cuts off communication between the top of cylinder 14 and discharge passage 31, and opens communication between cylinder 14 and passage 30 by way of the grooves 37' in the lower bearing member 37. It should be noted that the ungrooved portion 38' of the lower member 37 does not clear member 24 until after the portion 38' of the upper member 37 enters the bore of the member 22, so that at no time is cylinder 14 simultaneously open to inlet passage 30 and discharge passage 31.

As water is admitted into the upper end of cylinder 14, it overcomes the pressure on the underside of piston 15 because of the greater effective area on the upper side of said piston, and consequently, the piston 15 is forced downward until it reaches the position shown in Fig. 1. This completes a cycle of operations which will continue to repeat itself so long as the working load on the motor is insufficient to counterbalance the pressure differential between the upper and lower sides of piston 15. When this pressure differential is counterbalanced the piston will be stalled. However, no matter how slowly the piston may be moving and no matter in what position it may be stalled, whether it be midway of its stroke or whether at a point where ports 48 or 50 are barely cracked open, the distributor valve can never remain in an intermediate position but will always move either to the position shown in Fig. 1 or that shown in Fig. 2, and will maintain that position preventing leakage from passage 30 to exhaust passage 31, and furthermore, just as soon as the load on the motor is relieved, the piston 15 will automatically resume its reciprocating motion no matter in what position it had been stalled, and the valve mechanism will continue its cycle of operations from the point where it stopped.

It will be noted that a perfectly tight seal or, in other words, a perfect seating of the distributor valve on its seats, is provided by the spring washers 40, and it will be observed also that they accomplish a two-fold purpose, because aside from insuring a perfect seal by reason of their flexibility, they also assist because of their resiliency in initiating movement of the distributor valve. It is also to be noted that provision has been made to take up wear of sliding parts. As explained above, any wear between members 22 and 24 and the members 37, is taken up

or compensated for by the washers 40 which insure a perfect seating of the distributor valve regardless of whether it be canted out of actual alignment with the cylinder casting 21. Wear on the pistons 36 and 35' is taken up by the packings 33 and 34. It will be noted that these packings need only guard against leakage in one direction, viz upward and for this reason, I have used the cupped rings shown. It will be evident, however, that instead of introducing these rings into the cylinder walls they or their mechanical equivalents may be applied equally as effectively in the walls of the pistons 36 and 35', and hence I do not wish to limit myself to the exact construction shown in the drawings. The only other place in which wear that needs to be compensated for can occur, is between the slide valves 42 and their seats; but wear at these points is taken up automatically by the springs 47. Consequently, provision has been made for eliminating any difficulties due to wearing of parts and a tight seal against leakage of actuating liquid is insured at all times.

While I have shown a preferred embodiment of my invention, it will be understood that I do not limit myself to the precise details shown in the drawings, but consider myself at liberty to make such slight changes in construction or arrangements of parts as may fall clearly within the scope of definition of the following claims.

I claim:

1. A valve mechanism comprising a casting formed with two cylinders of respectively different bore and having inlet and outlet passages communicating respectively with said cylinders, a hollow piston member formed with two pistons adapted respectively to fit said cylinders and reciprocate therein, a flexible disk valve at each end of the piston member, seats for said valves formed on the casing, said valves serving to close communication between the interior of the casing and said inlet and exhaust passages alternately, the piston member being formed with ports for the admission and exhaust of fluid to actuate said member, and a slide valve operable to control said ports.

2. A valve mechanism comprising a casting formed with two cylinders of respectively different bore and having inlet and outlet passages communicating respectively with said cylinders, a hollow piston member formed with two pistons adapted respectively to fit said cylinders and reciprocate therein, a resilient disk valve at each end of the piston member, seats for said valves formed on the casing, said valves serving to close communication between the interior of the casing and said inlet and exhaust passages alternately, the piston member being formed with ports for the admission and ex-

haust of fluid to actuate said member, and a slide valve operable to control said ports.

3. A valve mechanism comprising a casting formed with two cylinders of respectively different bore and having inlet and outlet passages communicating respectively with said cylinders, a hollow piston member formed with two pistons adapted respectively to fit said cylinders and reciprocate therein, a valve at each end of the piston member, seats for said valves formed on the casing, said valves serving to close communication between the interior of the casing and said inlet and exhaust passages alternately, the piston member being formed with ports for the admission and exhaust of fluid to actuate said member, a pilot valve operable to control said ports, and means for operating said pilot valve.

4. A valve mechanism comprising a casting formed with two cylinders of respectively different bore and with inlet and outlet passages communicating respectively with said cylinders, a hollow piston member adapted to fit and reciprocate in said cylinders, a valve at each end of the piston member, seats for said valves formed on the casing, said valves being adapted by reciprocation of the piston member to close communication between the interior of the casing and the inlet and exhaust passages alternately, the piston member being formed with a valve seat on the interior face thereof, ports opening into said seat for the admission and exhaust of fluid to actuate the piston member, a slide valve engaging said last named seat and operable to control said ports, a carriage reciprocable within the piston member for supporting said slide valve, and a spring adapted to hold the slide valve in engagement with its seat.

5. The valve mechanism comprising a casting formed interiorly with cylindrical valve seats at opposite ends thereof, the casing being further formed with an inlet and an outlet passage opening into the interior thereof intermediate between said seats, and with two cylinders of respectively different bore between said passages and communicating therewith, a hollow cylindrical valve reciprocable within the casing to engage said seats alternately, said valve being formed with pistons adapted to fit said cylinders, said cylindrical valve being further formed with an inlet port communicating with the inlet passage, with an outlet port communicating with the outlet passage and with an intermediate port between said pistons, and a pilot valve for placing said intermediate port alternately in communication with the inlet port and the outlet port.

6. A valve mechanism comprising a casting formed interiorly with a cylindrical valve seat near each end thereof, and with an inlet and an outlet passage opening into

the interior thereof intermediate between said seats, the casing being further formed with two cylinders of respectively different bore between said passages and communicating therewith, a hollow cylindrical valve reciprocable within the casing to engage said seats alternately, said valve being formed with pistons adapted to fit said cylinders, said cylindrical valve being further formed 10 with an inlet port communicating with the inlet passage, with an outlet port communicating with the outlet passage and with an intermediate port between said pistons, a slide valve for placing said intermediate 15 port alternately in communication with the inlet port and the outlet port, the casing being further formed with face valve seats at opposite ends thereof, and flexible disk valves carried by the cylindrical valve and 20 adapted to engage said face seats alternately.

7. A valve mechanism comprising a casing formed interiorly with cylindrical valve seats at opposite ends thereof, the casing being further formed with an inlet and an outlet 25 passage opening into the interior thereof intermediate between said seats and with two cylinders of respectively different bore between said passages and communicating therewith, a hollow cylindrical valve reciprocable within the casing to engage said 30 seats alternately, said valve being formed with pistons adapted to fit said cylinders, said cylindrical valve being further formed with an inlet port communicating with the inlet passage, with an outlet port communicating 35 with the outlet passage and with an intermediate port between said pistons, a slide valve adapted to place said intermediate port alternately in communication with the inlet port and the outlet port, the casing 40

being further formed with face valve seats at opposite ends thereof, and resilient disk valves carried by the cylindrical valve adapted to engage said face seats alternately.

8. The combination with a motor cylinder 45 and a piston reciprocable therein, of a valve mechanism comprising a hollow head open to one end of the cylinder, the head being formed with inlet and outlet passages for the motor actuating fluid, a fluid actuated 50 sleeve valve reciprocable within the hollow head, supplementary flexible disk valves carried by the sleeve valve, said sleeve valve and disk valves co-operating to close communication between the motor cylinder and said 55 passages alternately, the sleeve valve being formed with ports for the admission and exhaust of fluid for actuating said valve, a pilot valve adapted to control said ports, and means associated with said piston for 60 operating said pilot valve.

9. The combination with a motor cylinder and a piston reciprocable therein, of a valve mechanism comprising a hollow head open to one end of the cylinder, the head being 65 formed with inlet and outlet passages for the motor actuating fluid, a fluid actuated sleeve valve reciprocable within the hollow head, resilient disk valves carried by the sleeve valve, said sleeve valve and disk 70 valves co-operating to close communication between the motor cylinder and said 75 passages alternately, the sleeve valve being formed with ports for the admission and exhaust of fluid for actuating said valve, a pilot valve adapted to control said ports, and means associated with said piston for 80 operating said pilot valve.

FREDERICK F. COUCH.
